INVENTOR

By Wm. Crumtree ATTORNEY

UNITED STATES PATENT OFFICE.

RICHARD BREUL, OF BRIDGEPORT, CONNECTICUT, ASSIGNOR TO SMITH & EGGE MANUFACTURING COMPANY, OF SAME PLACE.

DRAWER-PULL.

SPECIFICATION forming part of Letters Patent No. 258,882, dated June 6, 1882.

Application filed December 23, 1879.

To all whom it may concern:

Be it known that I, RICHARD BREUL, of Bridgeport, in the county of Fairfield and State of Connecticut, have invented certain new and useful Improvements in Drawer-Pulls; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to certain novel features of construction of drawer-pulls, as will be hereinafter and in detail explained.

In order that those skilled may know how to make and use my invention, I will proceed to describe its construction and application, referring by letters to the accompanying drawings.

Figure 1 is a front view of an ordinary drawer-pull; Fig. 2, a similar view of a drawer-pull embodying my invention; Fig. 3, a section taken at the line *y y* of Fig. 2; and Fig. 4, a detail view in section at line *x x*, Fig. 2, of one method of securing the hook end of the shank to the bar or pull which passes through the ferrule.

Similar letters denote like parts in the several figures of the drawings.

A represents the shank, which I prefer to make flat, oval, or such other shape in cross-section that it may be readily forced through a round hole bored in the front of the drawer or door and retained against turning.

B is an escutcheon, and C a drawer-front.

The rear end of the shank, or that portion which protrudes to the inside of the drawer-front, is formed with an elongated slot adapted to receive a keying-wedge, D, or it may be adapted to receive a screw-nut. The outer end of the shank is turned or bent into hook form and adapted to surround and grasp an ordinary ring, F, or cross-bar H. The escutcheon B is raised centrally to form an annular shoulder, which is covered by the open end of a ferrule, I, the outer end of which is closed and strengthened by pressing into any suit-

able shape, as clearly seen at Fig. 3. The 50 sides of the ferrule are penetrated by the bar H or ring F, and said ring or bar grasped by the hook end of the shank A, the escutcheon having a slot centrally to admit of the passage through it of said shank.

When the several parts referred to are arranged as described the free end of the shank A is forced into and through the hole prepared for it in the front of the drawer, and by the application of the keying-wedge D or a drawing screw-nut the ferrule is drawn against the escutcheon and the latter against the drawer-front, and are firmly held in position without the use of any other securing devices.

By reason of the shape in cross-section of 65 the shank, the shank and also the escutcheon are retained in a fixed axial relation. The shoulder on the escutcheon, embraced by the open end of the ferrule, prevents any sidewise movement of the ferrule, and also serves to 70 strengthen and support it against indentation. The ferrule thoroughly conceals and protects the connection between the shank and the ring or bar, and presents an ornamental appearance, and the length of the ferrule also 75 determines the distance of the ring or bar from the front of the drawer. The ferrule at that point where the ring or bar passes through it may be provided with an eyelet, around which the hook end of the shank passes, and any 80 desired form of pull may then be passed through said eyelet.

What I claim as new, and desire to secure by Letters Patent, is—

The ferrule I and shank A, connected together substantially as described, in combination with the escutcheon B, having a raised central portion or annular shoulder, the whole adapted to be held together and in position on a drawer by a key-wedge or nut, as hereinbefore set forth.

In testimony that I claim the foregoing as my own I hereby affix my signature in presence of two witnesses.

RICHARD BREUL.
